CLAIM

The ornamental design for a children's toy, as shown and described.

DESCRIPTION

FIG. 1 is a top perspective view of a children's toy; FIG. 2 is a front view of the children's toy of FIG. 1; FIG. 3 is a rear view of the children's toy of FIG. 1; FIG. 4 is a right side view of the children's toy of FIG. 1; the left side view being a mirror image thereof; FIG. 5 is a top view of the children's toy of FIG. 1; and, FIG. 6 is a bottom view of the children's toy of FIG. 1. The broken lines are included for the purpose of illustrating portions of the children's toy which form no part of the claimed design.
